UNITED STATES PATENT OFFICE.

MEREDITH G. STANLEY, OF CINCINNATI, OHIO.

HAND-STAMP.

1,153,351.

Specification of Letters Patent. Patented Sept. 14, 1915.

Application filed September 7, 1912. Serial No. 719,075.

To all whom it may concern:

Be it known that I, MEREDITH G. STANLEY, a citizen of the United States, residing at Cincinnati, in the county of Hamilton and State of Ohio, have invented certain new and useful Improvements in Hand-Stamps, of which the following is a specification, reference being had therein to the accompanying drawing.

This invention relates to hand stamps and has special reference to a stamp designed for the purpose of indicating upon a bill or receipt the amount received and, at the same time, registering the same amount on a paper strip carried in the interior of the casing.

The principal object of the invention is to improve the construction of the stamps described in my co-pending applications bearing the Serial Nos. 690,675; 694,887; and 694,918.

With the above and other objects in view as will be hereinafter apparent the invention consists in general of certain novel constructions, combinations and arrangements of parts, as will be hereinafter fully described, illustrated and claimed.

In the accompanying drawing like characters of reference indicate like parts in the several views, and Figure 1 is a transverse section through a hand stamp constructed in accordance with this invention. Fig. 2 is a section at right angles to Fig. 1. Fig. 3 is a section on the line 3—3, Fig. 2. Fig. 4 is a detail view of the reversing mechanism for the ink ribbon. Fig. 5 is a detail showing the front of the casing.

In carrying out the objects of the invention there is provided a casing 10. The bottom of this casing 10 is closed by a base 11 and the upper end of the casing is in like manner provided with a closing plate 12 having a centrally disposed opening 13 and lateral slots 14 adjacent its edges. At each side of the centrally disposed opening 13 there is provided a printing pad 15 which carries any suitable characters, as for instance the name of the firm or any other advertising matter that may be desired. Journaled in the walls of the casing is a shaft 16 whereon is revolvably mounted a series of gears 17. Adjacent one side of the casing is a shaft 18 whereon is revolvably mounted a series of indicator disks 19 which project through an opening 20 in the casing. Secured to each of the indicator disks is a

gear 21 which meshes with a respective gear 17. Just below the opening 13 there is provided a shaft 22 whereon is revolvably mounted a series of type wheels 23 each provided with a gear 24 which meshes with a respective gear 17. Below the shaft 16 is a shaft 25 provided with a series of type wheels 26 each of which has formed thereon a gear 27. Each of the gears 27 meshes with a respective gear 17 and the arrangement is such that the bottom character on the lower type wheel, the top character on the upper type wheel, and the character which shows through the opening 20 on the indicator wheel will always be the same. Journaled in the casing adjacent the top is a shaft 26 and directly below this shaft is a second shaft 27. On these shafts 26 and 27 are spools 28 carrying an ink ribbon 29 similar to the usual typewriter ribbon.

Pivoted to the casing as at 30 are arms 31 which carry a rod 32 and project slightly above the casing where they are provided with a platen 33 which extends over the top of the casing and is provided with a stamp handle 34. The lower end of the arms 31 are connected to bell crank levers 35 which carry a rod 36. The ink ribbon 29 is led from one of the spools up through one of the slots 14, passing in its route over a rod 37 and is then led across the face of the pad 15 and down over the rod 32 through the other slot 14 and beneath the rod 36 to the remaining spool 28. Depending from one arm of the bell crank lever 35 is a pair of links 38 which carry a platen roll 39.

Journaled in the casing are shafts 40 whereon are mounted spools 41 which carry a strip of paper 42. To the end of the bell crank lever 35 is connected a bar 43 which is provided with laterally extending arms 44. On the shafts 26 and 27 and one of the shafts 40 are ratchets 45, the two ratchets on the shafts 26 and 27 being of opposite hand. On the arms 44 and the bar 43 are pawls 46 which engage the respective ratchets 45. Slidably mounted within the casing is a bar 47 having at its top and bottom arms 48 which project over the spools 28. These arms are so spaced that both arms will constantly be in contact with the ink ribbon.

The bar 47 is provided with a slot 49 and adjacent this bar is mounted a bar 50 carrying a pin 51 which projects within the slot 49. This bar 50 is provided at each end with a cam surface 52 and these cam surfaces

52 engage pins 53 on the pawls 46 which control the movement of the spools 28.

In the operation of the device the type wheels are set by means of the indicator 5 wheels and the receipt or bill is placed beneath the platen 33. The platen is then depressed; this prints the required characters on the bill and, at the same time, the arms 31 cause movement of the levers 35. This 10 raises the platen 39 with the paper ribbon and brings this paper ribbon into contact with the ink ribbon at the point where it crosses the lower type wheels. At the same time this action raises all the pawls. Now, 15 when the platen 33 is relieved from pressure it again rises and the pawls will descend thereby actuating the respective ratchets. It is to be noted that one of the pawls 46 is always out of engagement so 20 that the ink ribbon can be fed. Now, when one of the spools 28 becomes filled the bar 47 will then move in one direction or the other by its filling until the pin 51 comes in contact with the respective end of the slot 25 49. This will cause movement of the bar 50 which will change the position of the cam surfaces 52 and thereby disengage the previously engaged pawl and allow the previously disengaged pawl to drop into engagement, thus reversing the direction of 30 movement of the ribbon 29. There has thus been provided a simple and efficient device of the kind described, and for the purpose specified.

35 Having thus described the invention, what is claimed as new, is:—

1. A hand stamp of the class described comprising a casing, type wheels carried by said casing, ribbon rollers carried by said 40 casing the ribbon carried thereby passing over said type wheels, recording strip-supporting rollers carried by said casing, a platen roller positioned below one of said printing rollers, and means supporting said 45 platen roller for drawing the same into engagement with one of said printing rollers for causing an impression to be made upon said recording sheet.

2. A stamp of the class described comprising a casing, a plurality of ribbon sup-

porting rollers carried thereby, a plurality of guiding rollers carried by the top of said casing, a guiding roller carried near the bottom of said casing, said ribbon passing over said guiding rollers, ratchet means for turning said ribbon rollers, a stamping platen, arms supporting said stamping platen, a bell crank frame pivotally secured to said casing and engaging said arms, depending links secured to said bell crank lever, a 60 platen roller secured to said depending links, a printing roller carried by the top of said casing and adjacent the bottom of said casing above said platen roller, record strip supporting rollers carried near the bottom 65 of said casing, and said stamping platen adapted to cause said platen roller to be drawn up into engagement with said printing roller as said stamping platen is compressed upon said casing.

3. A device of the class described comprising a casing, a plurality of indicating disks carried by one side of said casing, a printing disk carried by the upper end of said casing, a printing disk carried near the 70 lower end of said casing, an inking ribbon for the printing disks carried by said casing, inking ribbon guiding rollers positioned upon said casing, said inking ribbon passing over said rollers and in front of said upper printing disk, a stamp platen, arms supporting said stamp platen, bell crank levers pivotally secured to the sides of said casing and capable of being swung thereon, a platen roller secured below said bell crank 75 levers, a recording sheet passing over said platen roller, said platen roller adapted to be drawn up in engagement with said printing disk carried near the lower end of said casing as said hand platen is compressed 80 upon said casing, and means co-operating with said guiding rollers for automatically causing the ribbon to wind in an opposite direction.

In testimony whereof I hereunto affix my 85 signature in presence of two witnesses.

MEREDITH G. STANLEY.
